(57) CLAIM

The ornamental design for a cosmetic product package, as shown and described.

DESCRIPTION

FIG. 1 is a front perspective view of a cosmetic product package embodying the present design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines are provided for the purposes of illustrating an environment related to the cosmetic product package or parts related to the cosmetic product package that form no part of the claimed design.
